HEWITT L. WELLS, OF WASHINGTON, DISTRICT OF COLUMBIA, ASSIGNOR TO T-BEAM ENGINEERING COMPANY, OF WASHINGTON, DISTRICT OF COLUMBIA, A CORPORATION OF THE DISTRICT OF COLUMBIA.

CONCRETE FLOOR CONSTRUCTION.

Application filed December 22, 1921. Serial No. 524,052.

To all whom it may concern:

Be it known that I, HEWITT L. WELLS, of Washington, in the District of Columbia, have invented certain new and useful Improvements in Concrete Floor Construction; and I do hereby declare the following to be a full, clear, and exact description of the invention, such as will enable others skilled in the art to which it appertains to make and use the same.

My invention relates to concrete floor construction and particularly such as are reinforced in two directions and supported on reinforced concrete girders and columns or concrete and tile encased steel girders and columns. Because of the relative economy and simplicity of construction the flat slab type of floor has been largely used but it has been found, in analyses of such floors reinforced in two directions, that there are certain weaknesses which must be overcome to insure against initial failure and properly and more adequately distribute the reinforcement to further increase their load carrying capacity. It has been noted in such analyses, and especially in loading tests on slabs of this type, that high stresses are developed in the region of the corners of the panel adjacent to the column being indicated by openings or cracks in the bottom of the concrete slab and which radiate from the edges of the columns toward the center of the slab or panel. Investigation further discloses that the reinforcing bars in the bottom of the slab in proximity and close to the sides of the beams are not subject to stress and are not therefore of prime necessity to the strength of the structure and may therefore be eliminated. It is the object of my invention to produce a concrete floor construction wherein the slab shall be of a minimum thickness commensurate with the bending moment and deflection values and one embodying a proper and adequate arrangement and distribution of bar reinforcement in a manner to overcome the difficulties heretofore encountered, and such a floor construction wherein, within certain limits of span and loads, a lesser quantity of reinforcing material shall be required without detracting from the strength of the structure.

In the drawings, Figure 1 is a top plan

view showing the arrangement of the reinforcing elements for a floor panel or slab of solid concrete supported on reinforced concrete girders on four sides of the panel. Figure 2 is a sectional view through the center line of the panel shown in Figure 1. Figure 3 is an enlarged plan view of a column with the reinforcing elements for the corners of the panel. Figure 4 is a vertical section of a portion of two adjacent panels at their point of support on beams and column to indicate the arrangement of reinforcing elements at that point.

As is well known, concrete floors have heretofore been reinforced by bands of steel bars A and B, the bars A, forming one series, being arranged at right angles to the bars B, which form a second series, all of the bars of each series being supported by reinforced girders or beams, indicated at C, the ends of the bars framing into or extending over the beams and overlapping the bars of adjacent panels. It has been the practice heretofore to place the reinforcement the full width of the panel, the outside bars of each band being located close to the side of the respective girder. A study of the test data and conclusions drawn therefrom has indicated that the tensile stress in the bottom of the slab varies from a maximum at the center to zero near the beam parallel to the reinforcing members. The steel may therefore be advantageously distributed over only a part of the width of the slab. It is proposed to distribute most or all of the steel required in the middle three-fifths of the panel, although, to cover cases of possible unbalanced loading, 80% of the steel may be equally distributed over the middle three-fifths and 10% over each of the outer fifths.

The beams are ordinarily reinforced to provide for the shearing stresses by numbers of stirrups D which are bent up and extended into the overlying slab. By extending the ends of these stirrups a sufficient distance from the sides of the girders and parallel to the top of the slab provision is made for the negative stresses existing at that point over the top of the girder. The necessary negative reinforcement heretofore supplied by the bent up and extended ends of the slab bars lying at the outer edges

of the bands is thus taken care of by the combined stirrup and continuity reinforcement.

To provide against the initial failure by 5 tensile stresses occurring at the bottom of the slab at the corners of the panels I provide a reinforcing unit which is arranged so as to intersect the radii of the column within the angle defined by the supporting 10 beams, or otherwise stated a reinforcing element fitting within the corner between right angularly disposed beams or other supporting members. In Figure 3, three different forms of reinforcement are shown, 15 1 being a single bar bent back upon itself a number of times with the several lengths so formed lying in spaced parallelism. 2 shows a second form where several bars are arranged in spaced relation and so held 20 by a looped cross bar 3 to which they are appropriately wired, or these several bars may be held as shown in the third form, Figure 3, by a single cross bar 4. In this Figure 3 I have shown the various reinforcing elements of the beams in full lines and have omitted the parts of the stirrups 25 D all for the sake of clearness.

It is the customary practice to have part 30 of the bars in each beam straight and framed directly into the columns, as indicated at E while others, shown at F, are bent up and over the column into the adjacent beam to supply continuity. As will 35 be apparent from an examination of Figures 3 and 4 it is necessary that this corner reinforcing element, variously denoted 1 and 2, shall be easy to install at the point where so much steel reinforcing is centered and yet must be structurally correct. The 40 character of corner reinforcing described meets these requirements and effectively reinforces the panel at this point.

I claim as my invention:

1. A concrete floor including supporting 45 columns, beams spanning the space between such columns, and a concrete slab having a plurality of spaced apart reinforcing steel bars arranged in two series at right angles to each other and supported by said beams, 50 in combination with reinforcing elements at the bottom of the slab in the space adjacent said column defined by beams or other supporting means between columns lying at right angles to each other.

55 2. A concrete floor including supporting columns, beams spanning the space between such columns, and a concrete slab having a plurality of spaced apart reinforcing steel bars arranged in two series at right angles to each other and supported by said beams, 60 triangular reinforcing units located at the bottom of the slab in the corners thereof adjacent said columns.

3. A concrete floor including supporting 65 columns, beams or other supporting means

spanning the space between said columns, and a concrete slab having a plurality of spaced apart reinforcing steel bars arranged in two series at right angles to each other and supported by said beams or supporting means, in combination with a reinforcing frame of steel at the bottom of the slab in the space adjacent said column defined by beams or other supporting means between columns lying at right angles to each other. 70 75

4. A concrete floor including supporting columns, beams or other supporting means spanning the space between said columns, and a concrete slab having a plurality of spaced apart reinforcing steel bars arranged in two series at right angles to each other and supported by said beams or supporting means, in combination with a reinforcing frame formed with spaced lengths of steel bars arranged in parallelism at the bottom 80 of the slab in the space adjacent said column defined by beams or other supporting means between columns lying at right angles to each other. 85

5. A concrete floor including supporting 90 columns, beams or other supporting means spanning the space between said columns, and a concrete slab having a plurality of spaced apart reinforcing steel bars arranged in two series at right angles to each other 95 and supported by said beams or supporting means, in combination with a reinforcing frame formed with spaced and varying lengths of steel bars arranged in parallelism at the bottom of the slab in the space adjacent said column defined by beams or other supporting means between columns lying at right angles to each other. 100 105

6. A concrete floor including supporting columns, beams or other supporting means 110 spanning the space between said columns, and a concrete slab having a plurality of spaced apart reinforcing steel bars arranged in two series at right angles to each other and supported by said beams or supporting means, in combination with a reinforcing frame formed from a single steel bar bent to provide a series of spaced lengths arranged in parallelism at the bottom of the slab in the space adjacent said column defined by 115 beams or other supporting means between columns lying at right angles to each other.

7. A concrete floor including supporting columns, beams or other supporting means 120 spanning the space between said columns, and a concrete slab having a plurality of spaced apart reinforcing steel bars arranged in two series at right angles to each other and supported by said beams or supporting means, in combination with a reinforcing frame formed from a single steel bar bent to provide a series of spaced and varied 125 lengths arranged in parallelism at the bottom of the slab in the space adjacent said column defined by beams or other support- 130

ing means between columns lying at right angles to each other.

8. A concrete floor including, in combination with supporting columns, beams or other supporting means spanning the space between said columns, and a concrete slab having a plurality of spaced apart reinforcing steel bars arranged in two series at right angles to each other and supported by said beams or supporting means, stirrups formed from a single bar bent to provide double its cross-sectional area at the tops of the beams to provide for the negative tensile stresses at that point, the ends of the stirrups extending to some distance on either side, and a reinforcing element interposed in the space adjacent said column and lying in the bottom of the slab.
9. A concrete floor including, in combination with supporting columns, beams or other supporting means spanning the space between said columns, and a concrete slab having a plurality of spaced apart reinforcing steel bars arranged in two series at right angles to each other and supported by said beams or other supporting means, each

series being of less width than the span between beams paralleling its bars, the series being centrally disposed in such span, stirrups adjacent the end of each beam with their ends bent up and over the top of the beam and extending some distance beyond to provide for negative tensile stresses, and a reinforcing element interposed in the space adjacent said column and lying in the bottom of the slab.

10. A concrete floor including supporting columns, beams spanning the space between such columns, and a concrete slab supported by said beams and columns and having a plurality of spaced-apart reinforcing steel bars arranged in two series at right angles to each other, such reinforcing bars being supported by said beams, in combination with corner reinforcing elements for said slabs having each a plurality of lengths formed from a steel bar and arranged in a horizontal plane diagonal to the longitudinal axes of the supporting beams.

In testimony whereof I have signed this specification.

HEWITT L. WELLS.
